UNITED STATES PATENT OFFICE.

WILLIAM MASON, OF HARTFORD, CONNECTICUT, ASSIGNOR TO THE COLTS PATENT FIRE-ARMS MANUFACTURING COMPANY, OF SAME PLACE.

BREECH-LOADING FIRE-ARM.

SPECIFICATION forming part of Letters Patent No. 247,373, dated September 20, 1881.

Application filed May 12, 1881. (No model.)

To all whom it may concern:

Be it known that I, WM. MASON, of Hartford, in the county of Hartford and State of Connecticut, have invented a new Improvement 5 in Breech-Loading Fire-Arms; and I do hereby declare the following, when taken in connection with the accompanying drawings and the letters of reference marked thereon, to be a full, clear, and exact description of the same, and which said drawings constitute part of this specification, and represent, in—

Figure 1, a sectional side view of the parts in their normal condition; Fig. 2, the same with the breech open and the hammer in consequent cocked position; Fig. 3, transverse section through the barrels and rock-shaft.

This invention relates to an improvement in that class of arms in which the barrel is hung forward and so that the breech end tips up to open the cartridge-chamber, and known as "barrel tilting up at the breech," and with special reference to what are known as "concealed hammers"—that is, the hammer is within the receiver of the arm and cocked in the act of tilting the barrels.

The invention consists in the arrangement of a rock-shaft transverse to the barrels, and which is substantially the axis on which the barrels turn, the said shaft provided with a cam-like 30 radial projection, against which a corresponding projection on the barrel will press in the act of tilting, the said shaft in connection with the hammer, so that as the shaft rotates the hammer is thereby turned to full-cock, as more 35 fully hereinafter described.

A represents the frame or receiver, extending from beneath the barrels B, as at C, the forward end rounded to receive the forearm D in substantially the usual manner. In a recess in 40 the receiver the hammer E is hung upon a pivot, a, the upper end of the hammer arranged to strike a firing-pin, b; or it may be constructed with a projection which will pass through an opening in the breech end of the receiver to 45 strike the primer.

The mainspring is of usual V shape. One arm, d, rests against a stationary point in the receiver, the other end, e, resting upon the hammer forward of the pivot.

F is a transverse rock-shaft arranged at the

forward end of the receiver, beneath the barrel, and forming substantially the axis on which the barrels turn in tilting. On this rock-shaft a cam-like projection, f, is formed upon the upper side, and a similar cam-projection, h, below, 55 and on the under side of the barrel a projecting lug, l, is formed to hook over the rock-shaft, its front surface engaging the cams f & h, as shown, so that when the barrel is tilted the surface of the lug l above the pivot bears against 60 the cam f and turns the rock-shaft forward. Then, in returning the barrels, the surface of the lug on the other side of the rock-shaft bears upon the cam h and turns the rock-shaft in the opposite direction.

From the rock-shaft F an arm, L, extends rearward beneath an arm, P, which extends forward from the hammer, and so that when the barrels are closed, as in Fig. 1, and the parts in their normal condition, the hammer E 70 stands forward in the firing position, the arm P of the hammer resting slightly above the end of the arm L.

Tilting the barrels, or turning them from the position in Fig. 1 to that in Fig. 2, the rock-shaft is turned, as before described, which raises the arm L, and that, bearing against the arm P of the hammer, turns the hammer backward, as seen in Fig. 2, until it engages with the sear R. Then when the barrels are returned 80 the arm L also returns, leaving the hammer in the cocked position, from which it is released by the trigger in the usual manner.

It will be seen by those skilled in the art that instead of the rigid arm L on the rock-shaft 85 operating beneath the arm P of the hammer, other connections may be made between the rock-shaft and hammer, whereby the rotation of the rock-shaft by the turning of the barrel will cock the hammer. Such intermediate 90 mechanism will constitute the subject-matter of independent applications for Letters Patent which I am about to make.

While the two cams, f & h on the rock-shaft are preferred, it will be evident to those skilled in the art that the lower cam, h, may be dispensed with, the hammer after discharging serving to return the rock-shaft to its position before cocking, or the barrels may otherwise engage the rock-shaft.

It will be understood that while particularly designed for double-barreled sporting or shot guns, this device is applicable to single tilting barrels.

5 I claim—

In fire-arms in which the breech is opened by the barrel tilting up at the breech, the combination therewith of a transverse rock-shaft arranged substantially at the axis upon which

10 the barrel turns, an extension from the barrels into connection with said rock-shaft, so that

as the barrels are tilted said shaft will be turned, a hammer hung at the rear, and mechanism between said shaft and hammer whereby the tilting of the barrels and the consequent 15 rotation of the rock-shaft turns the hammer to full-cock, substantially as described.

WILLIAM MASON.
